[57] CLAIM

The ornamental design for an combined kinetic sculpture
and acoustical amplifier, as shown and described.

DESCRIPTION

FIG. 1 is a front perspective view of a combined kinetic
sculpture and acoustical amplifier showing my new
design;

FIG. 2 is a rear view thereof;

FIG. 3 is a top plan view thereof;

FIG. 4 is a right side view thereof;

FIG. 5 is a left side view thereof;

FIG. 6 is a bottom view thereof;

FIG. 7 is a front perspective view thereof, shown in an
alternate position for clarity of illustration;

FIG. 8 is a front perspective view thereof, shown in an
alternate position for clarity of illustration;

FIG. 9 is a front perspective view thereof, shown in an
alternate position for clarity of illustration.

FIG. 1

FIG. 2

FIG. 3

FIG. 4

FIG. 5

FIG. 6

FIG. 7

FIG. 8

FIG. 9
